COLLAPSIBLE RAFT

Joseph Jacus, Miami, Fla.

Application November 26, 1956, Serial No. 43,943

Term of patent 14 years

(Cl. D71—1)

FIG. 1

FIG. 2

FIG. 3

FIG. 4

FIG. 5

Figure 1 is a top plan view of a collapsible raft showing my new design.

Figure 2 is a front elevational view thereof.

Figure 3 is a rear elevational view thereof.

Figure 4 is a bottom plan view thereof.

Figure 5 is a side elevational view thereof.

I claim:

The ornamental design for a collapsible raft, substantially as shown.
